(57) **CLAIM**

We claim the ornamental design for an air deodorizing apparatus, as shown and described.

DESCRIPTION

FIG. 1 is an upper front perspective view of the claimed design for the air deodorizing apparatus;

FIG. 2 is an upper rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The ornamental design which is claimed is shown in solid lines. The broken lines shown in the drawings as surrounding the apertures are understood to represent the boundary of the claimed design. The remaining broken lines shown in the drawings are for illustrative purposes only and form no part of the claimed design.
